SOPHUS PETERSEN, OF BROOKLYN, NEW YORK, ASSIGNOR TO SPERRY GYROSCOPE COMPANY, OF BROOKLYN, NEW YORK, A CORPORATION OF NEW YORK.

MEANS FOR TRANSMITTING ANGULAR MOVEMENTS.

1,225,486.

Specification of Letters Patent

Patented May 8, 1917.

Application filed September 17, 1915. Serial No. 51,188.

To all whom it may concern:

Be it known that I, SOPHUS PETERSEN, a subject of the King of Denmark, residing at 369 Seventh street, Brooklyn, New York, have invented certain new and useful Improvements in Means for Transmitting Angular Movements, of which the following is a specification.

This invention relates to devices for transmitting the movements of one instrument or machine to another device situated at a distance therefrom. More particularly my invention has reference to rope or wire gearing wherein the pulleys around which the rope passes are of special construction to insure non-slipping of the rope.

While my invention is of the general application in the art of rope or belt gearing, it has especial advantages for connecting a sending or control instrument to a distant repeating or receiving instrument, which is caused to repeat accurately every movement of the control instrument.

Use for such devices is found in many types of mechanical annunciators and in aeronautic compasses of the type shown in the copending application of Lawrence B. Sperry, Serial No. 16721—steering device for air craft filed March 24, 1915, according to which the lubber's line of the compass is shifted to compensate for side drift of the aeroplane by an observer seated some distance therefrom. In such devices non-slipping of the transmission wire or rope is of prime importance. It is also of great advantage to have the transmission gearing of such a type that relative movement or translation of the two instruments will not affect it, that is so that it is not necessary to keep the connecting cord or wire taut. It is the main object of this invention to devise a form of mechanical transmission which is positive and reliable under all circumstances, wherein slippage or lost motion is abolished and at the same time freedom of movement is permitted.

Referring to the drawings, in which what I now consider the preferred form of my invention is illustrated, Figure 1 is a view of a portion of both the sending and receiving instruments, showing my transmission gear-

ing. In the device shown the two instruments are interchangeable.

Fig. 2 is a section on line 2—2 of Fig. 1.

Fig. 3 is a bottom view of one of the pulleys shown in Fig. 1.

Fig. 4 is a detached view of one of the disks or laminations used in the making up of a pulley.

Fig. 5 is a sectional view of a modification.

For the purposes of description, let it be assumed that 1 is the controller or sending instrument and 2 the receiving or repeating instrument. An indicator may be provided for each instrument. As shown the rope grip pulleys 3 and 4 on the instruments are provided with graduations 5 and 6 which are read in connection with indices 7. It is obvious that the indicator may be located on some other movable portion of the instrument, if desired.

Preferably the rope grip pulleys 3 and 4 are duplicates, so that only one need be described. Pulley 3 is mounted on a shaft 8 extending within the casing 9 of the instrument 1. A hand wheel 10 or equivalent means is provided to operate the pulley. In constructing the pulley, preferably a plurality of disks or laminations 11, 12 and 13 are used. The exterior disks 11 and 12 are provided with inwardly extending slits 14 around their edges forming fingers 20 whereby maximum resiliency and flexibility are secured. Spaced a small distance from their peripheries the said disks are provided with annular depressions 15, 16 which cooperate to form a restricted passage 19 for the rope 17, with the entrance thereto partially or wholly closed as at 18. The fingers 20 are designed to grip the rope tightly in passageway 19 and to positively prevent its escape therefrom. At their outer edges 21 the fingers 20 are bent outwardly or beveled to furnish means whereby the entrance 18 to passage 19 may be opened to allow entrance 95 or disengagement of the rope.

This feature is somewhat exaggerated in the drawings, in order to illustrate it clearly. The middle disk 13 is of somewhat less diameter than the other two, being used primarily to furnish a solid seat for the wire so that the wire will not spring the outer

disks apart and become wedged therebetween. All of the disks are firmly united as by rivets 30.

Preferably a positive means in the form of 5 a spreading device or wedge-like member is used to open entrance 18. Wedge-shaped rollers 22 are probably best suited for this purpose. These rollers are pivoted on brackets 23 secured to casing 3 adjacent the points 10 where the rope 17 enters and leaves the pulley, so that their wedge-like peripheries spread the fingers 20 by engaging between the outturned edges 21, and thus open entrance 18 to passage 19.

15 The flexible connector 17 preferably is made of wire, although cord or rope may also be used. In the claims I have used the word rope as a generic term to include all types of flexible connectors such as wire, 20 cable, cord, rope and round belts.

The intermediate portions of wire 17 between the two instruments 1 and 2 are incased in flexible tubing 25, secured adjacent each end to the instruments, preferably to 25 the brackets 23 described above. Tubing 25 may be wire wrapped as indicated by convolutions 26, and is designed to fit wire 17 so as to prevent buckling or kinking of the wire, but at the same time permitting 30 free longitudinal movement of the wire through the tube. By this means, in combination with my novel pulleys, it is no longer necessary to keep the flexible connector taut, but the two instruments may be 35 moved around at will. By this means I also secure the great advantage that the two instruments need not be placed so that the connecting wire is straight, but the wire can be laid in a curve in and around other objects without affecting the accuracy of the 40 repeaters.

Fig. 5 shows a modified form of friction pulley 3' in which only two disks 11 and 12 are used, this form being adapted for finer wire than the main form of the invention.

In accordance with the provisions of the patent statutes, I have herein described the principle of operation of my invention, together with the apparatus which I now consider to represent the best embodiment thereof, but I desire to have it understood that the apparatus shown is only illustrative and that the invention can be carried out by other means. Also, while it is designed to 55 use the various features and elements in the combination and relations described, some of these may be altered and others omitted without interfering with the more general results outlined, and the invention extends 60 to such use.

Having described my invention, what I claim and desire to secure by Letters Patent is:

1. A rope grip device comprising resilient

members adapted to grip a rope therebetween and a wedge positioned adjacent the point where the rope engages or leaves said members for spreading said members.

2. The combination with a rope grip pulley, of a wedge-shaped roller positioned adjacent the point where the rope leaves or engages the pulley for releasing the grip of the pulley on the rope.

3. A rope grip pulley comprising resilient members adapted to grip a rope therebetween, a wedge-shaped roller mounted adjacent the point where the rope engages or leaves said members adapted to hold said members in an open position at said point, as the pulley is rotated.

4. A rope grip pulley comprising a plurality of sheet metal disks at least one of said disks having a flared periphery provided with a plurality of slits and an annular depression, the disks being secured together so that the annular depression forms gripping jaws for the rope.

5. A rope grip pulley comprising a pair of sheet metal disks each of said disks having a flared periphery provided with a plurality of slits and an annular depression, the disks being secured together so that the annular depressions form gripping jaws for the rope.

6. A rope grip pulley comprising a plurality of flat sheet metal disks secured face to face, at least one of said disks having a flared periphery, provided with a plurality of slits and an annular depression, the disks being secured together so that the annular depression forms gripping jaws for the rope and a wedge for spreading said jaws at a predetermined point.

7. The combination with sending and receiving instruments, of transmitting mechanism therebetween including a pulley on each instrument comprising resilient, gripping flanges, a wire connecting said pulleys and spreading means for said flanges positioned adjacent points where the pulleys engage the wire.

8. The combination with sending and receiving instruments of transmitting mechanism therebetween including a pulley on each instrument comprising resilient, gripping flanges, a wire connecting said pulleys, a flexible covering for the intermediate portions of the wire and spreading means for said flanges positioned adjacent the points where the pulleys engage the wire.

9. A rope grip pulley comprising a plurality of disks, the outer disks being provided with annular depressions which coöperate to form a socket for the rope, and an inner disk of less diameter than said outer disks, forming a seat for the rope.

10. A rope grip pulley comprising a plurality of disks secured together, the outer

disks being provided with a plurality of peripheral slits and an inner disk of less diameter than said outer disks, forming a seat for the rope.

5 11. A rope grip pulley comprising a plurality of disks, the outer disks being provided with a plurality of peripheral slits and with annular depressions which coöp-

erate to form a socket for the rope, and an inner disk of less diameter than said outer 10 disks, forming a seat for the rope.

In testimony whereof, I have signed my name to this specification this 8th day of September 1915.

SOPHUS PETERSEN.
